UNITED STATES PATENT OFFICE.

WELLINGTON PARKER KIDDER, OF ROCHESTER, NEW YORK, ASSIGNOR, BY MESNE ASSIGNMENTS, TO ROCHESTER INDUSTRIES, INC., OF ROCHESTER, NEW YORK, A CORPORATION OF NEW YORK.

TYPEWRITER.

Application filed July 20, 1921, Serial No. 486,149. Renewed July 7, 1924.

To all whom it may concern:

Be it known that I, WELLINGTON PARKER KIDDER, a citizen of the United States, and resident of Rochester, in the county of Monroe and State of New York, have invented 5 certain new and useful Improvements in Typewriters, of which the following is a specification.

This invention relates to improvements 10 in typewriting machines; its main objects being to produce a shift mechanism for use in vertically shifting, either a vertically shiftable type head cage used in cooperation with an endwise movable paper carriage 15 that is not shiftable vertically; or in vertically shifting a vertically shiftable, endwise movable paper carriage in cooperation with type heads having rectilinear movement only; the type heads in each case having a 20 plurality of three printing characters spaced apart one above another.

In the accompanying drawings forming a part hereof and illustrating my invention:

25 Fig. 1 is a top plan view of the base and key lever guide construction of my new typewriting machine.

Fig. 2 is a transverse sectional view from front to back at line 2—2 of Fig. 1 of what 30 is shown in Fig. 1.

Fig. 3 is a top plan view of the machine in partial assemblage and particularly illustrates the type head cage construction and features of the cage shifting mechanism.

35 Fig. 4 is a transverse section from front to back at line 4—4 of Fig. 3 with a type head and type head actuating mechanism in place.

Fig. 5 is a vertical sectional elevation 40 from front to rear of the machine at line 4—4 of Fig. 3. This view shows a type head at impression point with the cage in its intermediate position with the intermediate printing character of three spaced 45 apart and vertically aligned printing characters at the impression point.

Fig. 6 is a transverse vertical sectional view in all respects like Fig. 5, except that the cage and cage actuating mechanism are 50 in their most elevated positions with the

lowermost printing character at the impression point.

Fig. 7 is a transverse sectional view in all respects like Figs. 5 and 6, except that the cage and the cage shifting mechanism are 55 in their lowermost positions with the uppermost printing character at the impression point.

Fig. 8 is an elevational view partly in vertical section at line 8—8 of Fig. 11 of 60 my new selective, tilttable, cage shift key lever.

Fig. 9 is a front elevation thereof.

Fig. 10 is an elevation of the vertically slotted front wall of the machine. 65

Figs. 11, 12 and 13 are side elevational views, respectively showing the cage shift key lever depressed to its fullest extent for depressing the cage to its lowest position; showing the cage shift key lever depressed 70 to its fullest extent for lifting the cage to its highest position; and showing the shift key in its highest position for positioning the cage at its intermediate position.

Fig. 14 is a top plan view showing the 75 shift mechanism installed for use in connection with a vertically shiftable paper carriage.

Figs. 15 and 16 are respectively a plan and an end elevation of an endwise slidable paper carriage carrying frame that does not have any vertical movement. 80

Fig. 17 is a cross-sectional elevational view at a line corresponding to line 8—8 of Fig. 3 and shows a non-swingable, stationary, type-head cage and the shift mechanism connected to a vertically shiftable paper carriage. This view shows the paper carriage in its normal position relatively to the intermediate printing character on a 90 type head.

Fig. 18 is a cross-sectional, elevational view at a line corresponding to line 4—4 of Fig. 3 and shows the paper carriage in said central, normal position; and illustrates the 95 paper carriage on its supporting frame and also illustrates, in connection with the paper carriage, the part of the shift mechanism which in Fig. 4 is shown connected to the swingable type cage.

Fig. 19 is a front elevational view of the end thrust lever adjusting means.

Referring to the drawings 1 indicates the up-standing end frames of the machine; and 5 2 indicates forwardly and rearwardly extending tie plates set edgewise and spaced laterally apart between the end frames. The forward end of each tie plate has a vertical flange 3 which is secured in place by a fastener 4 to a vertical portion of the transverse front wall of the machine. The rear end of each tie plate has a horizontal flange 5 which is fastened by a fastener 6 to the horizontal transverse bottom of a paper carriage guide-way, the rear up-standing transverse flange of which is indicated by 7. Forwardly of and spaced apart from said guide-way, the tie plates 2, the forward upper and under edges of which are respectively in 15 horizontal alignment, support upper and under arcuate and slotted transverse guide plates 8 the under plate having an up-standing flange 9 along its front edge. Each guide plate has an inwardly projecting horizontal tooth 10 and an intermediate guide slot 11. The teeth of the two guide plates 8 are in vertical opposition one to another and so also are their slots, the opposed edges of each of which form guide walls with which 20 the bell crank levers described below are in sliding contact.

The front vertical wall 12 of the machine is straight and located forwardly of the guide plates and rearwardly of the keyboard (Figs. 3 and 4). The vertical guide slots in the lower portion of the front wall 12 are severally for a key lever, and are indicated by 13, these slots alternating with vertical teeth 13^a to one of which each vertical flange 3 of the front end of a tie plate 2 are secured.

The tie plates 2 support a transverse arcuate pivot rod 15 which is located between the horizontal guide plates 8 adjacent the rear edges thereof. This pivot rod supports a series of bell crank levers each being part of a type head actuating mechanism. The two outermost tie frame plates 2 are bent and the intermediate one midway between the end frames is straight. The horizontal guide plate slots 11 and teeth 10 are all radial to the impression point which is midway between the side frames and each of the outermost frame plates 2 is provided with an outwardly projecting horizontal flange 16, the flanges being convergent in the radial direction and extending from a rear guide plate edge forwardly.

The front wall 12 extends above the level 60 of the upper guide plate 8 and the frames 1 are each formed at each forward upper corner portion with a transverse shaft supporting hole 17 in which there is mounted below, but adjacent, the transverse top flange 65 14 of the front wall 12, a transverse shaft

18 on which the forward end of the type head cage is hinged by three annuli 19, which are spaced apart along the length of the cage structure. The two outermost annuli are severally fixed to a forwardly extending end wing 20 of the cage, and the intermediate annulus 19 is fixed to the mid-sectional crown of the front and approximately vertical wall 21 of the cage, the two end wings 20 being angular forward extensions of the wall 21 and being parallel one to another. The bottom wall 22 of the cage is a flat type head supporting plate which extends transversely of the machine. The upper surface of this plate rearwardly of its front marginal portion is continuously smooth; that is, it is formed preferably without any type head guides or grooves and its upper back surface is the type head support. Its forward margin is formed, 80 between its ends, with a series of radial slots 23 which alternate with teeth 23^a. Each slot 23 is opposed to a slot 11 of each of the guide plates 8 and each tooth 23^a is opposed to a tooth 10 in each of the guide plates 8, 90 one of which is directly over the other. The cage is mounted above the upper horizontal guide plate 8. There are three slots one above another between the radial edge walls of each of which each bell crank lever described below is guided in reciprocating the type-heads. The top plate of the cage is indicated by 24 and its under surface is continuously flat or grooveless. Its forward margin is supported on transversely alined 100 ears of the front plate 21 and its rearward margin is supported by vertical spacing collars 25 and screws therefor between the forward marginal portion of the type-head supporting plate 22 of the top plate 24. The 105 type-heads stand vertical and are indicated by 26. Each is provided with three printing characters in vertical alinement and spaced apart on the rearward edge of the type-head. Each end of the type-head supporting plate 22 is provided with an integral arm 28 for the vertical spindle of a ribbon spool 29. Each forwardly extending wing 20 is provided with laterally projecting horizontal ears 30, each provided with a 110 fastener hole 31, and the upper margin of the front plate 21 is provided with horizontal ears 32 each having a fastener hole 331. The forward margin of the top plate 24 is fastened to the ears 32 and the ends of the 115 top plate are fastened to the ears 30. The 120

For each type-head there is pivotally mounted on the pivot rod 15 a bell crank lever 34 which projects upwardly and forwardly from the pivot rod 15 through a 125 guide slot 11 in the upper guide plate 8, and also through a slot 23 in the cage bottom wall or type-head supporting plate 22 and has its upper end pivoted at 35 to a type-head carrier 36 to which the type-head 130

is rigidly attached by rivets 37. Each bell crank lever is so dimensioned below the pivot rod 15 that the under surface of the bell crank lever also works in a guide slot 11 of the under guide plate 8. Thus, in the form shown, each bell crank lever is guided and restrained from lateral vibration by the edge walls in a slot in the type-head supporting wall, by edge walls of a corresponding slot in the upper guide plate 8, and below the pivot rod by the edge walls of a corresponding slot in the bottom guide plate 8.

The bell crank lever projects rearwardly of the pivot rod 15, and its rearward end is pivotally connected at 38 with a downwardly extending link 39 the under end of which is pivoted at 40 to an impression key lever 41 having an upturned rear end portion 42, the upper end of which is pivoted on a transverse horizontal pivot pin 43 carried in lugs 43^a projecting from the back side of the up-standing wall 7 of the paper carriage guide-way. Each bell crank lever 34 has connected to it, between the pivot rod 15 and its pivotal connection at 35 with a type head carrier 36, the rearward end 44 of a coiled spring 45, the forward end 46 of which is attached to the up-standing flange 9 of the under horizontal guide plate 8. The printing characters on the type head are indicated by 47.

The type head supporting or bottom plate 22 of the type head cage, has at one end of its under rear margin a bracket 48 to which there is pivoted at 49 the upper end of a downwardly extending link 50 the under end of which is pivoted at 51 to an intermediate portion of a rocker arm stop 52 the upper end of which is fixed on a transverse rocker shaft 53 the end portions of which are journalled in the side frames 1, under the rear of the horizontal bottom plate 22 of the cage and adjacent the front portion of the transverse paper carriage guide-way. Each bell crank or type-head actuating lever 34 has its forward end positioned above the supporting plate, the type-head being formed T-shape and one end of the type-head sliding on the plate while the rear end of its stem portion is held horizontally above the plate by the upper end of the bell crank or type-head actuating lever which is laterally guided as herein described. The type-head, however, is laterally unguided. While by the lateral guidance of the type-head actuating lever and by the effect of the relatively large contacting surfaces of the pivoted ends of the lever and type-head, the type-head may be reciprocated properly to the printing point, yet each of the so actuated type-heads has such a capacity of lateral movement that if a plurality of them are accidentally driven simultaneously to the impression point they will be severally

drawn back by their return springs. This capacity of what may be called automatic release and return from lateral contact of two or more type-heads at the impression point is of demonstrated practical importance for high speed work on machines embodying this invention.

As shown at the right hand of Fig. 3, the rocker shaft 53 has fixed to it at 54 a vertically disposed, two armed rocker lever 55. Each arm is alternately engageable by the upper and under arms 56 of an endwise movable, thrust lever 57 the forward end of which is supported in a vertically elongated slot 58 (see Fig. 7) in a vertically adjustable plate 59 mounted on the back side of the front wall 12 which is formed with a pair of vertically elongated and spaced apart slots 60 (Fig. 10) and is also formed with a slot 58^a opposed to the slot 58 in the plate 59. Clamping screws 61 through the plate and slot 60 serve to hold the plate 59 in a vertically adjustable manner on the inward side of the front wall 12 through the opening 58^a in which the forward end portion of the thrust lever projects. To a pin 62 on a side of the thrust lever 57 the front end of a coil spring 62^a is anchored, as shown in Fig. 7, and the rear end of this spring is hooked to an ear 63 on the front central portion of the two armed rocker lever 55. Towards its rearward end the thrust lever 57 is provided with an elongated slot 64 which embraces a pin 65 projecting from an end of the frame. This thrust lever stands approximately horizontal, and rearwardly of its pivotal support on the pin 65 its upper and under arms 56 are in the paths of the two armed rocker lever 55, the spring 62^a keeping an arm 56 in constant engagement with one or the other arm of the two armed rocker lever 55.

The rocker stop 52 is provided at its under end portion with a stop finger, the rearward face 66 of which is adapted to strike against the under front corner surface 67 of the bottom wall 68 of the paper carriage guide way.

The end thrust lever 57; the coil spring 62^a; the two armed rocker lever 55; and the rocker stop 52 being active in returning the cage from its raised or lowered position to its intermediate position. The end thrust lever and its spring 62^a constitute a means for holding the cage in its intermediate position between its highest position and its lowest position. The highest position of the cage corresponds to the lowest of the three printing characters on the type head, its intermediate position corresponds to the position of the intermediate character on the type head, and its lowest position corresponds to the uppermost of the three printing characters on the type head. In Fig. 5, the normal position of the cage is

shown, and in this position both arms 56 are in working contact with the two armed lever 55 above and below the rocker shaft 53; and the link 50, together with the two 5 armed lever are in vertical position, the rocker stop 52 being then in its intermediate position. The pivots 49 and 51 and the link 50 are then on dead centers and the rocker arms 55 stand vertical. In this position the 10 tension of the coil spring 62^a pulls the end thrust lever rearwardly, keeping its arms 56 in constant pressure against the front surfaces of the opposed arms of the two armed lever 55. In Fig. 6 showing the 15 lowermost of the three printing characters at the printing point the link 50 is inclined upwardly and backwardly, the upper thrust lever arm 56 is in contact with the upper rocker arm 55, the under thrust lever 56 is 20 out of engagement with the under rocker arm 55 and the rocker shaft 53 has been rocked in a forward direction until the rocker arm stop 52 has moved rearwardly and upwards into engagement with the under side 25 of the front margin 67 of the bottom wall 68 of the paper carriage guide-way.

In Fig. 7 the uppermost of the three printing characters is at the printing point with the back edge of the plate 22 adjacent 30 the upper edge of the forward flange of the paper carriage guide-way, the stop 52 being then in its lowest position, the link 50 downwardly and rearwardly inclined, and the under thrust lever arm 56 being in contact with the under rocker arm 55 and the upper thrust lever arm 56 being out of contact 35 with the upper rocker arm 55.

Thus, the end thrust lever, the spring 62^a and the two-armed rocker lever having the 40 arms 55 have a cooperative effect whenever the case shift mechanism is actuated in holding the cage bottom in a predetermined position selected by the operator of the case shift key, with reference to the relative type-writing effecting position of any one of the 45 three characters and an opposed portion of the platen. In effect, the automatically operating end thrust and rocker arm construction just described constitutes an automatic mechanism for holding each of the three 50 printing characters at the impression point during the final imprinting movement of the type-head; and the operation of this automatic mechanism is governed by its 55 mechanical connection with the case shift mechanism about to be described.

At the left hand end of Fig. 3, the case 60 shift mechanism is shown in operative connection with the transverse rocker shaft 53. The cage shift key lever 69 is upturned at both ends and at the upward bend of its inward end it is provided with a transverse pivot hole 70, the diameter of which is 65 larger than the diameter of the pin 71 on which it is pivoted. The pin 71 projects

from the left hand end frame. The pin 71 is shown in the form of a headed screw (Fig. 8) an end of which is secured in the end frame with the body of the pin projecting inwardly. Adjacent the inner surface of 70 the frame it is provided with a loose collar 72 which is spaced apart from the head 73 of the screw to form a horizontal bearing on which the shift key lever 69 is pivotally mounted for approximately vertical movement, and is also tiltably supported for a purpose described below. To the left hand end (Fig. 3) of the transverse rocker shaft 53 there is fixed a transverse two armed lever 74 the under arm of which is indicated 80 by 75 and the upper arm by 76 (Fig. 11). To the end of the upper arm 76 there is pivoted at 77 the rear end of an upper forwardly extending link 78 which between its ends is bent edgewise downwardly at 79 and formed with a forward extension which is lengthwise slotted at 80, this slotted portion terminating forwardly in a lateral free hooked end 81. To the under end of the under arm 75 of the two armed rocker 90 lever 74 there is pivoted at 82 a forwardly extending under link 83 corresponding to the link 78 but having an upward bend at 84 forward of which there is a portion 85 in which there is formed a lengthwise extending slot, a dotted line portion of which is indicated by 86 in Fig. 12. The slots 80 and 86 are approximately laterally opposed one to the other and through each slot there projects a horizontal screw 87 from the left hand end frame, this screw supporting both links 78 and 83 in working position. The under link 83 at its front end has a laterally inturned free hooked end 81^a which corresponds and is opposed to 105 the hook end 81. The opposed end surfaces of the two hook ends are spaced slightly apart; and the shift key lever 69 has its upper rear end portion indicated by 88 projecting upwardly between the forward end 110 portions of the links 78 and 83 as a blade, the forward edge of which is opposable to the back surface of each laterally projecting hook end 81 and 81^a. (Fig. 3.) The hooked ends 81 and 81^a are opposed but 115 spaced slightly apart and the blade end portion 88, however, is never in operative contact with but one of the hooked ends at a time. A coil spring 89 (Fig. 11) has one end secured to the shift key lever 69 between 120 its pivot and rocker hole 70 and its upper end 88, the coil spring extending rearwardly and having its rearward end anchored on a pin 91 which projects from the end frame. As shown in plan in Fig. 3 the coil spring 125 89 is positioned so as to slant away from the inward surface of the frame end to which it is anchored at 91. The upper link 78 may correspond to the numerals on the type head and the link 83 may correspond 130

to the capitals on the type head, and in Fig. 3 I show the blade end portion 88 behind the hook end 81^a of the link 83. This is, under the assumed conditions, the normal 5 position of the cage shift key lever which is used selectively by rocking it laterally to carry its blade end 88 out of position for engagement on its depression with the hooked end 81^a and into position for engagement 10 with the hooked end 81 and vice versa. Between its front end and its pivotal bearing at 71 the key lever 69 is shown passing through a guide 92 which is dimensioned to permit the lateral tipping of the 15 key lever as already described. The upturned free end of the cage shift key lever 69 is provided with a button 93 to be characterized, and with an adjacent upstanding finger thrust ear 94, the two being for depression and lateral tilting of the cage shift key lever according to the election and selection of the operator.

As will be seen in Figs. 14 to 18, my paper carriage shift mechanism without material 25 modification is equally applicable to shifting the carriage vertically instead of shifting the type cage.

Referring to Figs. 17 and 18, my flat type head supporting plate 22 is made stationary, 30 extends from side to side of the machine and is secured on the upright side members 1, by screws 22^a or other fasteners. The vertical wall 21 of the cage is secured to this as previously described, and also the top 35 plate 24. The guide plates 8 are hung under the plate 22 and fastened thereto by vertical spacing collars 25 and screws therefor.

To a pair of rearward rocker arms 95 (Fig. 14) rigidly secured to the rocker shaft 40 53 there are rigidly attached a long transverse carriage supporting rail 106 slotted and pinned at 107 to the arms 95.

A convenient form of paper carriage supported on rail 106 comprises a frame F having upstanding end fork arms 103 (Fig. 15), the frame being endwise slidable on guide-ways 7 and to be provided with the usual escapement rack and escapement, neither of 45 which is shown.

Each pair of vertical fork arms 103 form a vertical guide-way 108 at each end of the frame. A guide block 104, in which an end of the platen P is journaled, is slidably mounted in each guide-way.

The carriage supporting rail 106 is loosely embraced by a lengthwise extending, U-shaped channel iron guide open along its front side. The back web of this guide is indicated by 96. Its forwardly projecting flange is indicated by 97 and its forwardly projecting upper flange by 98. Its back web 96 is fixed to a dependent web 99 of the paper carriage frame, the upper margin of the web 99 being fixed at 100 to the usual back, transverse paper rest 101 of the carriage.

The vertical shift positions of the rail 106 loosely embraced by the channel iron guide are controlled and actuated as previously described.

Stops 109 and 110 on a frame end serve 70 to limit the downward and upward shift positions, the stop 109 arresting the downward motion of an arm 95 and the stop 110 arresting the forwardly projecting arm 111 (Fig. 19) which is integral with a rocker 75 arm 95.

The mechanism hereinbefore described has an automatic type-head positioning mechanism, and the mechanism hereinbefore described has case shift mechanism which 80 together constitute a complete case shift mechanism in the broader aspect of the invention, and it will be convenient hereafter to refer in the broader claims to a shiftable member of the typewriting effecting mechanism as definitive either of a vertically shiftable paper carriage and platen with a non-vertically movable type-head, or of a paper carriage having endwise movement only and a type-head that has vertical movement for presenting any one of its plurality 90 of printing characters to the printing point, in addition to its printing pressure movement. As shown in Figs. 14 and 15, and also in other figures, the vertical type-head 95 26 has its under end sliding on the type-head supporting under plate 22 of the cage, which is smooth surfaced. The type-head itself is tiltable on its under end in the fore and aft direction, and the type-head carrier 36 which is rearward extension of the type-head and a portion of the type-head structure is pivoted by a pivot pin 35 to the upper end of the type-head actuating lever 34. The pivotal connection is one in 100 which the continuous walls of the pivot pin holes in the lever 34 and type-head carrier 36 peripherally enclose the pivot pin. And as shown in Figs. 14 and 15, on the forward reciprocatory movement of the type-head structure and actuating lever the front walls of the pivotally jointed connection of the lever and carrier strike against a noise-absorbing cushion or pad 21^a which is fixed to and carried by the under front rigid corner walls of the cage. The return movement of the thus connected type-head structure and its actuating lever is, in reality, arrested by the pad against the tension of the return spring 45 which, except for the 110 pad, would cause the parts on the return movement to strike violently and noisily against the immediately adjacent wall portions of the cage, unless such portions were spaced apart from the most forward possible position of the actuating lever 34 and the front end of a carrier 36 by an undesirable distance.

What I claim is:

1. The combination, in a typewriting ma- 130

chine, of a shiftable member of the typewriting effecting mechanism with a key controlled shift-mechanism for such member; said shift mechanism comprising a connection operatively connected with said shiftable member, and also comprising a rocker shaft having a fixed, two armed lever; a pair of endwise movable pivoted links, one connected with one end, and the other connected with the other end of the two armed lever; a laterally movable pivoted shift key lever operatively connectible at the will of the operator with either link; a return spring; the rocker shaft also having a fixed stop-forming device; and, for cooperation with such device, a thrust lever mechanism; a type-head supporting plate provided with a series of radial slots the side walls of which severally serve as a guide for a type-head actuating lever; a series of type-head carriers reciprocable on the plate; a series of type-head actuating levers each pivoted to the front end of a type-head carrier and extending downwardly through one of said slots with its sides in guiding contact with the side walls of the slot; a fixed pivot for the under end of said lever; an impression key lever operatively connected with each type-head actuating lever and a return spring for each type-head actuating lever.

2. In the combination set forth in claim 1, means for adjusting the position of the thrust lever.

3. The combination, in a typewriting machine, of an endwise movable platen; a type-head having a plurality of spaced apart printing characters; a type-head supporting plate having a guide slot; a bell crank lever working through said slot, having its sides in sliding contact with opposed edges of said guide slot, being pivoted on a fixed pivot under the supporting plate and being operatively connected with the type-head; an impression key lever operatively connected with the bell crank lever; a return spring therefor; a slotted guide plate for the bell crank lever between its pivotal connection with the impression key lever and a type-head supporting plate, the platen and type-head being movable relatively one to the other for opposition of a portion of the platen to a type-head character selected for impression; a case shift mechanism for effecting such selected opposition of the platen and a character, the shift mechanism comprising an accessible, manually operable, vertically movable and laterally tilttable shift key and a pair of links selectively engageable by the shift key at the will of the operator, and also comprising rockable means whereby said opposition to a selected character and of the platen are obtainable.

4. The combination, in a typewriting machine, of an endwise movable platen; a type-

head having not less than three spaced apart printing characters; a type-head supporting plate having a guide slot; a bell crank lever working through said slot, having its sides in sliding contact with opposed edges of the guide slot, being pivoted on a fixed pivot under the supporting plate and being operatively connected with the type-head; an impression key lever operatively connected with the bell crank lever; a return spring therefor; a slotted guide plate for the bell crank lever below the supporting plate, the platen and type-head being movable relatively one to the other for opposition of a portion of the platen to a type-head character selected for impression; a case shift mechanism for effecting such selected opposition of the platen and a character shift mechanism comprising an accessible, manually operable, vertically movable and laterally tilttable shift key and a pair of links selectively engageable by the shift key at the will of the operator, and also comprising rockable means whereby said opposition of a selected character and of the platen are obtainable; and an automatically operating mechanism for holding the intermediate printing character in printing position.

5. In a typewriting machine, the combination of an endwise movable, paper carriage with a swingable type head cage; a shift key controlled mechanism for positioning the cage in printing position; slidably mounted within the cage, a type head comprising three printing characters spaced apart one above another; and a type head actuating mechanism comprising an impression key lever, a bell crank lever working through an opening in the bottom of the cage and having a pivotal connection with the type head; a return spring; for the bell crank lever a horizontal pair of fixed guides; and for the impression key lever a fixed vertical guide.

6. In the combination set forth in claim 3, the shift mechanism being constructed and operable to hold the cage in position for impression by the intermediate character on the type head; and being also operable for shifting the cage from such intermediate position to a lower position and also to a higher position.

7. In a typewriting machine, the combination of a paper carriage comprising a platen; type-head supporting means comprising a flat type-head supporting plate provided with a radial slot in its front marginal portion; a laterally unguided type-head having a plurality of aligned printing characters; a dependent type-head actuating lever pivotally connected to the type-head and extending downwardly through said radial slot; a fixed pivot for the under end of the lever; and an impression key lever operatively connected with the type-head actuating lever.

the sides of the latter being in sliding contact with the side walls of the radial slot for restraining lateral vibration of said lever between its under pivoted end and its upper 5 pivotal connection with the type-head, the fixed pivot being below the type-head supporting plate.

8. In a typewriting machine, the combination of a type-head supporting plate provided with a radial slot in its front marginal portion; a laterally unguided type-head slideable on said plate to and from the impression point; a type-head actuating lever pivotally connected to the front end of the 10 type-head structure and extending downwardly through the radial slot, the edges of the latter being severally in lateral guiding contact with a side of the actuating lever; an impression key lever with which the 15 actuating lever is operatively connected; and a guide plate having a radial slot below the type-head supporting plate and through which the type-head actuating lever extends, the side walls of such under plate being in 20 guiding contact with the sides of the type-head actuating lever between its under pivot and its pivotal connection with the type-head structure.

9. In a typewriting machine, the combination of a type-head supporting plate provided with a radial slot in its front marginal portion; a laterally unguided type-head slideable on said plate to and from the impression point; a type-head actuating lever pivotally connected to the front part of the 25 type-head structure and extending downwardly through the radial slot; a guide plate having a radial slot below the type-head supporting plate and through which the type-head actuating lever extends, the side walls of such plate slot being in guiding contact with the sides of the type-head actuating lever between its under pivot and its pivotal connection with the type-head 30 structure; and a lowermost radial slotted guide plate located below the under stationary pivot of the type-head guiding lever, the side walls of such lever being in guiding contact with the side walls of the radial slot 35 of said lowermost plate below the fixed pivot of the type-head actuating lever.

10. The combination of a type-head supporting plate having a rearward plain surfaced type-head end supporting portion and a guide slot radial to the printing point forwardly of the type-head end supporting portion; a type-head having an end slidably mounted on the type-head supporting portion and also having a rigid forwardly projecting shank above and out of contact with 40 said plate; pivoted to the forward end of the type-head shank, a dependent type-head actuating lever working through said slot and having its sides in lateral engagement 45 with the side walls of the slot; below the

plate a fixed pivot for said type-head actuating lever; and operatively connected with the under end of said lever, an impression key lever; and a return spring operatively mounted for restoring the type-head to position of rest following impression; the pivotal connection of the type-head shank with the upper end of the type-head actuating lever comprising lateral vibration resisting surfaces whereby the type-head shank is reciprocable without undue lateral vibration. 70

11. The combination of a type-head supporting plate having a rearward plain surfaced type-head end supporting portion and a guide slot radial to the printing point forwardly of the type-head end supporting portion; a type-head having an end slidably mounted on the type-head supporting portion and also having a rigid forwardly projecting shank above and out of contact with 80 said plate; pivoted to the forward end of the type-head shank, a dependent type-head actuating lever working through said slot and having its sides in lateral engagement with the side walls of the slot; below the 85 plate a fixed pivot for said type-head actuating lever; and operatively connected with the under end of said lever, an impression key lever; and a return spring operatively mounted for restoring the type-head to position of rest following impression. 90

12. In a typewriting machine, the combination of a platen; a series of laterally unguided type-heads severally movable to the impression point of the platen; for the 100 type-heads, a smooth surface support having a slot for upward extension therethrough of a type-head actuating lever for each type-head; a series of such actuating levers, each pivotally connected with a type-head above the support; stationary guides for the opposed sides of each actuating lever; and under the support, operatively connected with each actuating lever, an impression key lever; whereby a plurality of type-heads if 105 forced simultaneously to the impression point into contact one with another will be then movable sidewise for several automatic return under the influence each of a return spring; and for each type-head actuating 110 mechanism a return spring.

13. In a typewriting machine, the combination of a platen; a series of laterally unguided type-heads severally movable to the impression point of the platen; for the 120 type-heads, a smooth surface support having a slot for upward extension therethrough of a type-head actuating lever for each type-head; a series of such actuating levers, each pivotally connected with a type-head above 125 the support; stationary guides for the opposed sides of each actuating lever; and under the support, operatively connected with each actuating lever, an impression key lever; whereby a plurality of type-heads if 130

forced simultaneously to the impression point into contact one with another will be then movable sidewise for several automatic return under the influence each of a return spring; and for each type-head actuating mechanism a return spring; each type-head having a forwardly projecting stem out of contact with the support and having its under end in sliding contact with the support; the forward end of the stem and the upper end of the actuating lever being pivoted together and provided with opposed bearing surfaces adjacent the pivotal connection; and the return spring having one end connected to the actuating lever and the other end connected to a stationary part of the machine.

14. In a typewriting machine, the combination of a type-head supporting plate adjacent the impression side of a platen; a platen; a laterally unguided type-head structure having a straight head provided with a printing character, an end of the head being slidably supported and also for-
20 wardly and backwardly tiltable on its end that rests on the support; a type-head actuating lever pivotally jointed at one end to a front portion of the type-head structure by a peripherally enclosed pivot pin, the other
25 end of the type-head actuating lever being pivoted on a fixed pivot; an impression key lever operatively connected with the actuating lever; a return spring; and between the pivoted ends of the actuating lever, means
30 for laterally guiding the actuating lever in its backward and forward reciprocating
35

movements, the actuating lever being at an angle to the path of movement of the type-head and having its fixed pivot below such path.

15. In a typewriting machine, the combination of a type-head supporting plate adjacent the impression side of a platen; a platen; a laterally unguided type-head structure having a straight head provided with a printing character, an end of the head being slidably supported and also forwardly and backwardly tilttable on its end that rests on the support; a type-head actuating lever pivotally jointed at one end to a front portion of the type-head structure by a peripherally enclosed pivot pin, the other end of the type-head actuating lever being pivoted on a fixed pivot; an impression key lever operatively connected with the actuating lever; a return spring; and between the pivoted ends of the actuating lever, means for laterally guiding the actuating lever in its backward and forward reciprocating movements; and in the path of the front walls of the pivotally jointed portions of the actuating lever and type-head structure a noise-reducing and structure arresting pad; and stationary means for holding the pad in place, the actuating lever being at an angle to the path of movement of the type-head and having its fixed pivot below such path. 45 50 55 60 65

Signed at New York city in the county of
New York and State of New York this fif-
teenth day of July A. D., 1921.
